Samuel J. Smallman, New York, N. Y.

Application October 3, 1944, Serial No. 115,573

Term of patent 7 years

(Cl. D87—3)

To all whom it may concern:

Be it known that I, Samuel J. Smallman, a citizen of the United States of America, residing in New York, county of New York, and State of New York, have invented a new, original, and ornamental Design for a Back for Billfold or Similar Article, of which the following is a specification, reference being had to the accompanying drawing, forming part thereof.

The figure is a plan view of a back for billfold or similar article showing my new design.

I claim:

The ornamental design for a back for billfold or similar article, substantially as shown.

SAMUEL J. SMALLMAN.
